KNOCKDOWN CRATED CARTON

Walter C. George, St. Louis, and Frederick R. Buhrmaster, Webster Groves, Mo., assignors to Gaylord Container Corporation, St. Louis, Mo., a corporation of Maryland

Application October 26, 1940, Serial No. 362,981

3 Claims. (Cl. 217—13)

This invention relates to knockdown crated shipping cartons. It has for its principal objects to devise a simple and inexpensive lightweight shipping carton of the above type which will knock down to form a compact package, which may be quickly and easily assembled and which is strong and rigid and well protected at its corners. The invention consists in the knockdown crated carton and in the parts and combinations and arrangements of parts hereinafter described and claimed.

In the accompanying drawings, which form part of this specification and wherein like symbols refer to like parts wherever they occur,

Fig. 1 is a top plan view of a knockdown crated shipping carton embodying our invention, 15

Figs. 2 and 3 are elevations of two adjacent sides of said carton,

Figs. 4 and 5 are vertical sections on the lines 4—4 and 5—5, respectively, in Fig. 1,

Fig. 6 is an enlarged horizontal cross-section on the line 6—6 in Fig. 2,

Figs. 7 and 8 are perspective views looking at opposite sides of one of the end closure sections of the carton,

Fig. 9 is a perspective view of one of the two folding body sections of the carton.

Fig. 10 is an edge view, showing the folded body sections and the two end closure sections stacked one upon the other,

Fig. 11 is a fragmentary perspective view showing a modified corner cleat construction for the corner formed by the scored intermediate portion of the body section,

Fig. 12 is a horizontal cross-section on the line 12—12 in Fig. 11; and

Fig. 13 is an edge view of the modified body section in the flat.

Our knockdown crated carton comprises duplicate sections A, each forming two adjacent side walls of the rectangular body of the carton, each of the body sections A comprises a single rectangular strip 1 of corrugated board, fiberboard or like material divided by a score line 2 into a side wall panel 3 and a side wall panel 4, whereby said side wall panels are adapted to fold one upon the other in the manner shown in Fig. 10.

Secured flatwise to the outer face of the side wall panel 3 along the free end thereof is a wooden cleat 5 whose ends are flush with the longitudinal edges of said panel and whose outer side edge is disposed outwardly beyond said end of said strip a distance corresponding substantially to the thickness thereof and is provided with extensions in the form of outstanding dowels 6.

Secured flatwise to the outer face of the side wall panel 3 with its outside edge flush with the score or hinge line 2 is a wooden cleat 7 whose ends terminate flush with the longitudinal edges of the corrugated board strip 1.

Secured flatwise to the outer side face of the side wall panel 4 along the free end thereof is a wooden cleat 8 that extends equal distances beyond the longitudinal edges of said panel and has its outer edge disposed outwardly of said end of said panel a distance corresponding to the thickness of the cleat 5. As shown in the drawings, the cleat 8 has dowel holes or recesses 9 in the inner side face thereof between the outer side edge thereof and the adjacent free end of the strip 1. Secured flatwise to the outer side face of the side wall panel 4 with its outside edge disposed outwardly beyond the score line 2 a distance corresponding to the thickness of the cleat 7 on the side wall panel 3 is a wooden cleat 10 that extends beyond the longitudinal edges of the strip 1 the same distance as the cleat 8 at the free end of the side wall panel 4.

The upper and lower or longitudinal edges of 25 the side wall panels 3 and 4 of each folding body section A are preferably strengthened, stiffened and protected by means of cleats 11 that extend from end cleat to end cleat of the respective side wall sections flush with said edges. The fastening means for the cleats of each body section 30 preferably comprise staples or nails 12 that are driven through the corrugated board strip 1 from the inner side thereof into said cleats.

As shown in Fig. 10, each of the two body 35 sections A of the carton may be folded along the score line 2 to bring the two side wall panels thereof into contact flatwise, thereby forming a compact package for shipment to the packer. In assembling the body of the carton, the two 40 side wall panels of each folded body section A are swung away from each other along the score line 2 as a hinge and brought into position at right angles to each other to form two adjacent side walls of the cartons. In this opened or 45 unfolded position of each body section A, the cleat 7 abuts edgewise against the cleat 10 with its outer side face flush with the outer side edge of the latter, thus completely enclosing the corner formed by the two side wall panels 3 and 4 of said body section. The two unfolded sections A are then assembled to form the hollow 50 rectangular body of the carton by bringing the end cleat 5 of each body section in edgewise abutting relation to the inner face of the end cleat 8 of the other section and entering the dowels 6 of

the cleat 5 into the holes 9 in the cleat 8, thus bringing the outer side face of the cleat 5 flush with the outer edge of the cleat 8. With the two body sections thus assembled, the cleats 5 and 8 of the two body sections cooperate to form two diagonally opposite corners of the crating for the body of the carton and the cleats 7 and 10 form the two remaining corners of said crating. The cooperating corner cleats 5 and 8 are secured together preferably by glue and/or nails 13 driven through the overlapping margin of one cleat into the abutting edge of the other cleat. If desired, the corner cleats 7 and 10 may be secured together in a similar manner.

The carton is provided with duplicate top and bottom closure members B each comprising a rectangular piece of corrugated board, fiberboard or like material 14 having wooden slats or cleats that are secured flatwise to the inner face or surface thereof flush with the edges thereof and cooperate to form a rigid edge frame 15 that snugly fits within the hollow rectangular body portion of the carton. If desired, the side walls of the body of the carton may be secured to the edge frame 15 of each end closure B by nails 16 driven through the cleats 11 and the fiberboard strips A into said edge frame. Secured flatwise to the outer face or surface of the corrugated board portion 14 of each end closure B flush with two opposite edges thereof are wooden cleats or slats 17 that extend beyond the other two edges thereof. One end of each of the cleats 17 seats against the end of the corner cleat 5 and terminates flush with the outer side face thereof and abuts edgewise against the inner side faces of the projecting end of the adjacent corner cleat 8. The opposite end of the cleat 16 cooperates in a similar manner with the corner cleats 7 and 10. Both of the end closure cleats have their outer faces disposed flush with the projecting ends of the corner cleats 8 and 10. The end closures are secured in place preferably by means of wood screws 18 which extend through the projecting ends of the cleats 17 and are threaded into the ends of the corner cleats 5 and 7 abutting thereagainst. The edge frame 15 of each end closure is secured thereto preferably by nails 19 that are driven through said frame and end closure into the cleats 17 and thus also secure said cleats to said end closure.

Figs. 11 and 12 illustrate a modified arrangement of corner cleats at the corners defined by the hinged or scored intermediate portion of the corrugated board strip 1 of each of the two body sections A. In this construction, the wooden corner cleat 1a that is located entirely on one side of the score line 2 is spaced therefrom and has its outer edge rabbeted, as at 1b, along its inner corner; and the other wooden corner cleat 10a has the portion thereof that is disposed opposite said rabbeted edge, grooved, as at 10b, from end to end. By this arrangement, the rabbeted margin of the cleat 1a and the grooved margin of the cleat 10a are spaced away from each other in the unfolded position of the body section and said margins and the corrugated board strip together form an undercut or T-shaped vertical groove between said cleats adapted to slidably receive a key or locking member in the form of a wooden strip 20 of substantially T-shaped cross-section. With this modified corner construction, the folding body section of the carton may be laid out flat for its entire length, while the locking key 20 serves, in the set-up position of the body section, to close the gap between the corner cleats 1a and 10a and to hold the corner square. The locking strip 20 is of the same length as the cleat 1a and terminates flush with the upper and lower end thereof and is adapted to be held against endwise movement in the T-shaped groove by the projecting end portion of the closure cleat 11 that is secured to said corner cleat by the screw 18.

The hereinbefore described carton has several important advantages. The overlapping cleats 5 and 8 at the cooperating free ends of the two body sections A and the two remaining corners formed by the overlapping cleats 7 and 10 adjacent to the score lines 2 along which the two sections are bent provide closed corner constructions that are strong and rigid and protect the carton material from becoming damaged in handling. The arrangement of corner cleats adjacent the score line of each body section permits the two side wall panels thereof to be folded or doubled one upon the other to form a compact package. In cases where inner packing is required to protect or hold the article in the carton, such packing may be easily inserted before the second body section is placed in position. The end closures are reinforced and stiffened by the cleats thereon and serve to prevent the carton from being distorted or thrown out of square; and these cover cleats, together with the cleats along the top and bottom edges of the side walls of the carton, serve to strengthen and stiffen said edges.

Obviously numerous changes may be made without departing from the invention. Therefore, we do not wish to be limited to the precise construction shown.

What we claim is:

1. A knockdown crated carton comprising a rectangular body, said body comprising two separate sections of corrugated board, fiberboard or the like, each of said sections being scored along one line only to provide two adjacent side walls of said body and to permit said side walls to fold one upon the other in knockdown form, separate cleats secured flatwise to the outside face of each of said corrugated board body sections at opposite ends thereof, the end cleats of one section lapping and being secured to the end cleats of the other section at two diagonally opposite corners of said body, and separate cleats secured to the outside face of each of said corrugated board body sections adjacent to and on opposite sides of the score line thereon, the longitudinal edge of one of the last named cleats being flush with said score line and the longitudinal edge of the other of said last named cleats projecting beyond said score line whereby said last named cleats are automatically brought into overlapped relation at one of the two remaining diagonally opposite corners of said body when said section is unfolded along the score line thereon to form two adjacent side walls of said body.

2. A knockdown crated carton comprising a rectangular body, said body comprising two sections only of corrugated board, fiberboard or the like, each of said sections being scored along one line only to provide two adjacent side walls of said body and to permit said side walls to fold one upon the other in knockdown form, separate cleats secured to opposite ends of each of said corrugated board body sections, the end cleats of one section being secured to the end cleats of the other section at diagonally opposite corners of said body, and cleats secured to said corrugated board body sections adjacent to and on opposite sides of the score lines thereon and adapted to be brought into overlapped relation at the

remaining corners of said body in the body forming position thereof, the cooperating end cleats at each of said diagonal corners being disposed one with its outer side edge in abutting relation to the inner face of the other, one of said cooperating end cleats having dowels on the outer side edges thereof that fit within holes provided therefor in the abutting inner side face of the other end cleat.

3. A knockdown crated carton comprising a rectangular body and an end closure therefor, said body comprising two sections only of corrugated board, fiberboard or the like, each of said sections being of uniform width from end to end and scored along one line only to provide two adjacent side walls of said body and to permit said side walls to fold one upon the other in knockdown form, cleats secured to opposite ends of each of said sections, the end cleats of one section being secured to the end cleats of the other section at diagonally opposite corners of said body, and cleats secured to each of said

sections adjacent to and on opposite sides of the score line thereon, the cleats on two opposite side walls projecting beyond the closure receiving end of said rectangular body and the cleats on the 5 two remaining opposite side walls terminating flush with said end, said end closure comprising a rectangular piece of corrugated board, fiberboard or like material, cleats secured to the outer face of said corrugated board piece along two 10 opposite edges thereof with their ends extending beyond the two remaining opposite side edges thereof and secured to the flush ends of the cleats on said two remaining opposite side walls and with their outer side edges abutting directly 15 against the projecting end of the cleats on said first mentioned opposite side walls, and a continuous edge frame secured to the inner face of said corrugated board piece and snugly fitting within said end of said rectangular body.
